MECHANICAL DOOR STOP MEANS
 William F. Knapp, Haughton, La.
 (908 Wanda Drive, Bossier City, La.)
 Filed Oct. 7, 1960, Ser. No. 61,243
 10 Claims. (Cl. 292—266)

This invention relates to the general field of limiting the pivotal movement of one element with respect to a fixed stationary member and, more specifically, the instant invention pertains to the provision of means for locking a door at any degree of opening or closing with respect to its associated fixed or stationary door jamb.

Another object of this invention is to provide improved means for securing a door or other closure member in a closed position or at any desired angle with respect to a door jamb when open.

Still another object of this invention is to provide a device of the type briefly described above which is operable in conjunction with conventional door handles.

A further object of this invention is to provide a door check or devices for retaining a door or gate in any desired open position, the door check being operable automatically from a door latch or door knob to permit the door to freely and easily swing from the door jamb while the door check means are rendered inoperable.

A further object of this invention is to provide means for securing swinging doors, window sashes, and the like, in a closed position or at any angle with respect to a door jamb when pivoted to an open position, and latching the securing means against casual displacement when the door or window sash, or similar device, is moved to an open position.

Another object of this invention is to provide a mechanical door stop which will obviate the above-noted disadvantages inherent in the constructions of prior art devices, and wherein the door check or stop will hold a door or other closure member from opening or closing at any degree of its arc of movement.

Still another object of this invention is to provide a mechanical door stop or check which may be automatically operated by the turning of a handle; that is, when the handle is turned to effect an opening of a door or closure member, the operation of the handle automatically releases the locking mechanism to permit the door or closure member to be pivoted to an open position, and when the handle is in its neutral or released position, the door or closure member becomes automatically locked.

It is still another object of this invention to provide a mechanical door stop which may be readily attached to the conventional doors of automobiles, houses, cabinets, et cetera.

This invention contemplates, as a still further object thereof, the provision of a door stop or check wherein the mechanism for operating the same may be placed in a chase or mortise in the door or between the side walls thereof whereby the motif or design on either side of the door is not affected.

This invention has, as another object thereof, the provision of door stop or door check means of the type referred to supra, wherein the means is non-complex in construction and assembly, inexpensive to manufacture, and durable in use.

Other and further objects of the instant invention will become more evident from a consideration of the following specification when read in conjunction with the annexed drawings, in which:

FIGURE 1 is a fragmentary side elevational view of a conventional automobile body including a door partially broken away and illustrating this invention as incorporated therein;

2

FIGURE 2 is a bottom plan view of the door stop or check, FIGURE 2 being taken substantially upon the horizontal plane of line 2—2 of FIGURE 1, looking in the direction of the arrows;

5 FIGURE 3 is a detail cross-sectional view of the door stop or check, FIGURE 3 being taken substantially upon the line 3—3 of FIGURE 2, looking in the direction of the arrows;

FIGURE 4 is a detail cross-sectional view of the door 10 stop or check illustrated in FIGURE 1, FIGURE 4 being taken substantially on the vertical plane of line 4—4 of FIGURE 3, looking in the direction of the arrows;

15 FIGURE 5 is a fragmentary detail cross-sectional view of means operable to hold the door latch or door stop means in inoperative position, FIGURE 5 being taken substantially on the horizontal plane of line 5—5 of FIGURE 1, looking in the direction of the arrows;

FIGURE 6 illustrates the adaptation of the instant invention to a conventional house door;

20 FIGURE 7 is an enlarged detail cross-sectional view of the door and door stop or latch illustrated in FIGURE 6, FIGURE 7 being taken substantially on the horizontal plane of line 7—7 of FIGURE 6, looking in the direction of the arrows;

25 FIGURE 8 is an enlarged end elevational view of the door locking or latching mechanism shown in FIGURE 6, FIGURE 8 being taken substantially on the vertical plane of line 8—8 of FIGURE 7, looking in the direction of the arrows; and

30 FIGURE 9 is a side elevational view partly broken away, FIGURE 9 illustrating a second embodiment of this invention.

Referring now more specifically to FIGURES 1 to 5, inclusive, reference numeral 10 designates, in general, a door stop or check constructed in accordance with the teachings of this invention. The door stop 10 is shown in conjunction with the conventional automobile door 12 and is disposed between the inner and outer door panels 14, 16, respectively. Means (not shown) of a conventional type secure one end of the door stop 10 to the upright end wall 18 of the door 12, the end wall 18 being provided with a substantially rectangular opening 20 to serve a purpose to be described infra. The end wall 18 is normally disposed in confined relation relative to a door jamb 22 when the door 12 is in its normally closed position.

In most conventional automobiles, handle or button means are utilized to operate a normally horizontally reciprocating door locking bolt. The arrangements are 35 many and do not, per se, constitute a part of this invention. However, and for the purpose of illustration of the present invention, reference numeral 24 designates a conventional door handle which is depressible to actuate a door bolt (not shown), through suitable mechanisms, 40 to move the bolt to its unlocked position. Connected to this mechanism or to the bolt is one end of an elongated strip member 26 supported for reciprocation adjacent its other end on a pin 28 which extends transversely between the door panels 14, 16 and engages within an elongated longitudinally-extending slot 30. The underside of the strip member 26 is recessed to provide a shoulder 32 extending transversely thereof and a longitudinally-extending tongue 34. Thus, as the handle 24 is depressed to unlock the door 12, the strip member 26 is moved to 45 the right, as viewed in FIGURE 1. Supported on a pin 36 which extends transversely between the panels 14, 16 (see FIGURES 1 and 5) is a bell crank lever 38 and a normally depending arm 40 on which is secured a roller 42. The roller 42 engages the shoulder 32 beneath the 50 tongue 34 and is constantly biased for movement in a clockwise direction, reference again being made to FIGURE 1, by virtue of means to be described below, where-

by the roller 42 maintains constant engagement against its adjacent shoulder 32. It will be understood, of course, that with the shifting movement of the strip member 26 to the right, the bell crank lever 38 pivots counterclockwise against the force exerted by the aforementioned biasing means.

The other arm 44 of the bell crank lever 38 is laterally offset from the arm 40. As is seen in FIGURES 1 and 5, means are provided to serve a purpose to be described which cooperate with the free end of the arm 44 to prevent the bell crank lever 38 from pivoting clockwise under the influence of said biasing means when the strip member 26 is moved to the left, reference being made to FIGURE 1, that is, in a direction away from the roller 42. The pivotal lock comprises a journal 46 secured by means 48 to the inner door panel 14, the journal 46 having pivotally mounted therein a shaft 50. One end of the shaft 50 terminates in a handle 52 which extends through an opening (not shown) formed in the panel 14, and the other end of the shaft 50 has rigidly secured thereto a disc 54. The connection between the disc 54 and the shaft 50 is off-center, whereby rotation of the shaft 50 effects a swinging movement of the disc 54. The relationship between the disc 54 and the free end of the arm 44 is such that when the bell crank lever 38 is rotated in a counterclockwise direction the disc 54 may be moved by manual manipulation of the handle 52 into the downward path of movement of the free end of the arm 44 thereby effectively preventing and locking the bell crank lever from moving in a clockwise direction. The purpose of these locking means will become more apparent as this specification progresses.

The door check or stop proper comprises a channel-shaped main body portion 56 having oppositely-disposed longitudinally-spaced and confronting end walls 58, 60 integrally connected together by a bight wall 62. The bight wall 62 adjacent each of the end walls 58, 60 is provided with slots 64, 66, respectively, the end walls 58, 60 being slotted at 68, 70, respectively, the slots 68, 70 being disposed in alignment, one with the other.

The end walls 58, 60 are slotted at 72, 74, respectively, the slots 72, 74 extending perpendicular to the slots 68, 70 and opening, at their inner ends, into the slots 64, 66, respectively. To serve a purpose to be described below, the bight wall 62 is formed with the longitudinally-extending bore 76 which terminates in a socket 78 in the end wall 60, and as seen in FIGURE 2 of the drawings, the bore 76 continues at 80 through the end wall 58.

The end members 58, 60 are provided, respectively, with substantially cylindrical downwardly-opening guide pockets 82, 84.

Referring now more specifically to FIGURE 4, reference numeral 86 denotes, in general, an inverted substantially U-shaped guide member having the opposed ends thereof disposed within the slots 68, 70, the guide member 86 including a pair of oppositely-disposed, spaced and parallel depending arms 90 connected along one of their adjacent longitudinally-extending sides by means of a bight member 92. The arms 88, 90, adjacent each end of the guide member 86 are provided with a pair of confronting notched-out portions 94, 96, the function of which will be made apparent below.

The bight member 92, also adjacent each end thereof, is formed with transversely-extending bores or openings 98, 100 which are adapted, when the guide member 86 is properly located, to align with the guide pockets 82, 84. The bight member 92 has, spaced inwardly from the bores 98, 100, a pair of recessed spring-keeper recesses 102, 104.

Disposed for reciprocation within the guide member 86 is an elongated substantially rectangular ratchet bar 106 having inclined and downwardly-extending ratchet teeth 108 extending substantially throughout its length. Projecting upwardly from each end of the ratchet bar 106 are a pair of guide pins 110, 112 which normally have the

free ends thereof slidably received within the bores 98, 100, respectively, and upon certain circumstances, the guide pins are capable of being moved or extended into the guide pockets 82, 84 when the ratchet bar 106 is moved in a direction toward the bight member 92. Interposed between the bight member 92 and the adjacent side of the ratchet bar 106 are a pair of helicoidal springs 114, 116, one end of the spring 114 being received within the spring-keeper recess 102 while the other spring 116 has one of its ends received within the spring-keeper recess 104. As is clearly seen in the drawings, the other ends of the springs 114, 116 engage against the ratchet bar 106 and constantly bias the ratchet bar 106 for movement in a direction away from the bight member 92.

The ratchet bar 106 is provided with a pair of bosses 118 which project from that side thereof oppositely disposed with respect to the pins 112. As is seen in the drawings, the bosses 118 are disposed immediately adjacent each end of the ratchet bar 106.

A shaft 120 (see FIGURES 2, 3 and 4) extends through the end wall 58 and the bight 62, the shaft 120 traversing the slots 64, 66, and having an end received within the socket 78 formed in the end wall 60. Mounted on the shaft 120 are the hubs 122 of a pair of levers 124, the hubs 122 being disposed within the slots 64, 66 and are fixedly secured to the shaft 120 for rotation therewith by means of set screws 126. The levers 124 are pivotally received within the slots 72, 74, and the free ends thereof constantly engage against and ride on the rounded bosses 118.

The other end of the shaft 120 terminates in a crank arm 128, and the construction is such (reference being made to FIGURE 4) that when the crank arm 128 is rotated in a counterclockwise direction, the shaft 120 will rotate in the same direction causing the free end of the lever 124 to pivot and, through its engagement with the bosses 118, force the ratchet bar 106 to move inwardly toward the bight 92 against the tension of the springs 114, 116.

Slidably mounted on the inverted substantially U-shaped guide member 86 and encompassing the ratchet bar 106 is a substantially rectangular slide member 130 having internal teeth 132 adapted to mesh with the teeth 108 of the ratchet bar 106 in various adjusted positions relative thereto. It will be understood from the foregoing description that when the crank arm 128 is pivoted in a counterclockwise direction, the teeth 108 will become disengaged from the teeth 132, thereby permitting the slide member 130 to move longitudinally of the guide member 86. Rotation of the crank arm 128 in the reverse, or clockwise direction, will cause engagement of the teeth 132 with the teeth 108, thereby locking the slide member 130 in a given position.

A lever 134 has one of its ends pivotally secured to the slide member 130 by means of a screw 136 and washer 138. The other end of the lever 134 is pivotally connected at 140 by means of a rivet, or other suitable connection, to a tongue 142 which projects outwardly from the door jamb 22 through an opening 144, the tongue 142 forming an integral part of a bracket plate 146, the latter being fixedly secured to the door jamb 22 by means of rivets 148.

One end of a lever 150 is pivotally connected with the free end of the crank arm 128 and is retained thereon by means of a cotter pin 152. The pivot pin 154, or any other conventional means, is utilized to connect the other end of the lever 150 to the bell crank lever arm 44 adjacent the outer end thereof. As is seen in FIGURE 1, the lever 150 passes behind the tongue 34, and it is for this reason that the arm 44 is offset with respect to the arm 40.

Axial displacement of the ratchet bar 106 is prevented by means of filler blocks 156, 158 which are disposed within the slots 68, 70, adjacent each end of the ratchet bar 106, and the filler blocks are held in their respec-

tive positions by means of screws 160 which extend therethrough and through the end walls 58, 60.

The assembly of the door stop or check 10 is completed by providing inverted, substantially U-shaped shock absorbers 162 which are fixedly secured to the end walls 58, 60 and which embrace the inverted, substantially U-shaped guide member 86.

Having described the first embodiment of this invention in detail, it is believed that the operation thereof is self-evident. However, and briefly summarizing the same, it will be understood that when the handle 24 is depressed, the strip member 26 is caused to move laterally to the right, as viewed in FIGURE 1 of the drawings. Movement of the strip member 26 causes pivotal movement of the bell crank lever 38 in a counterclockwise direction, and in so moving, the lever 150 is raised. Since the lower end of the lever 150 is connected to the crank arm 128, the shaft 120 will be caused to rotate in a counterclockwise direction, as viewed in FIGURE 4, thereby causing the lever 124 to pivot in the same direction. Since the free ends of the levers 124 engage against the bosses 118 of the ratchet bar 106, the ratchet bar is forced inwardly toward the bight 92 of the inverted U-shaped guide member 86. This occurs against the tension of the helicoidal springs 114, 116. As the ratchet bar 106 moves inwardly, its teeth 108 are disengaged from the teeth 132 formed on the slide member 130, thereby freeing the same for sliding movement longitudinally of the guide member 86.

As soon as the ratchet bar 106 has been disengaged from the slide member 130, the operator may now exert force on the door 12 in a direction such as to cause the same to open. As the door 12 pivots about its respective pivot points (not shown) in the conventional manner, the lever 134 will also pivot and in so pivoting will cause the slide member 130 to move longitudinally of the guide member 86.

The degree to which the door 12 is opened will determine the relative position of the slide member 130 with respect to the guide member 86. When the door is in its fully-opened position, the slide member will abut against the resilient shock absorber 166 at the extreme right-hand side of FIGURE 3 of the drawings, or if it should be desired to open the door 12 only partially, the slide member 130 will resume a position intermediate the two resilient shock absorbers 162 and 166.

The operator, upon opening the door 12 to the desired degree, then releases the handle 24, whereupon the same returns to its original position. The return of the handle 24 draws with it the strip member 26.

It must now be remembered that the helicoidal springs 114, 116 are so positioned as to bias the ratchet bar 106 in a direction away from the bight 92 and toward the teeth 132 of the slide member 130. Thus, when the ratchet bar teeth 108 effect engagement with the teeth 132 of the slide member 130 a force is exerted upon the levers 124 causing them to pivot in the reverse, or clockwise direction. Clockwise movement of the levers 124 introduces the same pivotal movement to the shaft 120 and this, in turn, rotates the crank arm 128 in such a direction as to draw downwardly the lever 150. Since the lever 150 is pivotally connected to the bell crank lever arm 44, the bell crank lever 38 will pivot in a clockwise direction and will maintain contact of the roller 42 with the shoulder 32 of the strip member 26.

With the teeth 108 of the ratchet member 106 engaged within the teeth 132 of the slide member 130, when the latter has been moved to an adjusted position, further outward movement of the door 12 is prevented. However, the operator may, when so desired, pull the door 12 to its closed position without further actuation of the handle 24. This, is, of course, in accordance with the conventional operation of ratchet mechanisms.

It should also be noted at this point that any sudden forward movement of the vehicle will, under the force of

inertia, tend to effect an automatic closing of the door 12.

Depending upon circumstances, the opposed vertical ends of the slide member 130 are provided with threaded screw openings 164, 166, to optionally receive therein screws 136. Thus, the lever 134 may extend longitudinally of the underside of the main body portion 56 or, the door stop 10 may be inverted from its position shown in FIGURES 1 and 3.

As has been set forth above, means are provided for rendering the door stop or latching mechanism in an inoperative position. To this end, the operator need but to depress the handle 24 to cause the arm 44 to pivot upwardly. Thereafter, the handle 52 is pivoted from the dotted-line position shown in FIGURE 5 to its full-line position illustrated therein, whereby the disc 54 moves under the free end of the arm 44. In so moving, the lever is pulled upwardly causing either of the bars 106, 106' to move out of engagement with the slide members 130, 130'. The door 12 is, thus, free to rotate about its pivotal axis without hindrance.

The modification of this invention, as illustrated in FIGURE 9 of the drawings, is identical with respect to the first embodiment with but minor changes formed therein. Consequently, elements shown in FIGURE 9 having counterparts in the first embodiment may be distinguished therefrom through the addition of prime marks to the elements in common.

In the embodiment of the invention shown in FIGURE 9, the bar 106' is provided with a plurality of depending rack gear teeth 170 which are adapted to mesh with rack gear teeth 172 formed on the slide member 130'. With this construction the door 12 of the vehicle is positively locked in its fully-open, fully-closed, or an intermediate-open position, and the ratchet feature, as described above, is omitted. In this last case, the door handle 24 must be operated each time the door 12 is moved to its closed position, or to any open position. In all other respects the inventions are identical.

FIGURES 6 to 8, inclusive, illustrate an application of either of these two embodiments described above to a conventional door. The door is herein designated by the reference numeral 200 and is hingedly connected at 202 in the conventional manner to a door jamb 204. The door 200 includes the usual door stiles 206 between which extend the usual door rails 208. The latter are disposed in laterally-spaced relation and between the same is located either of the above-described door checks or stops 10, 10'. Any conventional means may be employed for securing the door stop 10 to one of the rails 208.

In this application of the invention, the strip member 134 is pivotally connected at 210 to an eye screw 212 fixedly secured within the door jamb 204.

The shaft 120 terminates, in this application, in a lever 214 disposed substantially at right angles to the shaft 120 and the free end thereof terminates in an angular offset portion 216 substantially flat in configuration. The flat end 216 normally engages against the low side 217 of a cam, generally designated at 218. The cam 218 is fixedly secured to one end of an elongated shaft 220 which extends between the rails 208 and is fixedly secured thereto and supported therefrom by means of journals 222.

Reference numerals 224, 226 denote the high sides of the cam 218, and it will be understood that as the shaft 220 is rotated to bring one or the other thereof into engagement with the free end 216 of the lever 214, the co-action therebetween will cause the shaft 120 to rotate in a counterclockwise direction to effect movement of the ratchet bar 106 or the rack gear bar 106' toward the bight 92 of the guide member 86. The door 200 is, thus, free to pivot from the full-line position shown in FIGURE 7 to its dotted-line position as illustrated therein.

Means are provided for effecting the rotation of the shaft 220 from either side of the door 200. These means comprise doorknobs 228, 230 connected for rotation, one

with the other, by means of a shaft 232, the shaft 232 being connected with the conventional door-bolt actuating mechanism 234 which forms no part of the instant invention.

Fixedly secured to the shaft 232 for rotation therewith is a bevel gear 236 which meshes with a second bevel gear 238 rigidly secured to the shaft 220. Thus, as either of the knobs 228, 230 is rotated to effect a withdrawal of the door bolt 240 from the door jamb 242, the shaft 220 is caused to rotate, and in so rotating to effect clockwise movement of the lever 214 whereby the door stop or latching mechanisms are free to move relative to one another. Rotation of the shaft 220 in the opposite direction will, of course, cause the slide member 130, or 130' to be engaged by the teeth carried on the bar 136, 15 106' to hold the door 200 in any adjusted degree of opening desired by the operator.

Having described and illustrated in detail, several embodiments of this invention, it is to be understood that the same are offered merely by way of example, and that this invention is to be limited only by the scope of the appended claims.

What is claimed is:

1. A door stop for use on a door adapted to be hinged to a door jamb, comprising an elongated guide member adapted to be attached to said door in the manner extending normally to said door jamb when said door is in its normally closed position, a sliding block member slidably mounted on said guide member, a lever having one of its ends pivotally connected to said sliding block member and having its other end adapted to be pivotally connected to said door jamb at a position offset from the axis of rotation of said door on its hinges, means for locking said sliding block member on said guide member at any position of travel of said sliding block member and comprising a mechanism connected to manually-operable door latch means, said mechanism including a reciprocable strip member positioned to slide in a path offset from, but parallel to said guide member, said strip member terminating in a shoulder, a bell crank lever pivotally mounted on said door and having one of its arms terminating in a roller adapted to contact said shoulder of said strip member, and a vertically-extending actuating member connected to the other arm of said bell crank lever and connected to said means for locking said sliding block member on said guide member, whereby said means for locking said sliding block member on said guide member may be operated by said manually-operable door latch means.

2. A door stop comprising an elongated guide member for attachment to a hinged door, said guide member being disposed substantially normally to the door jamb to which said door is hinged, a sliding block member slidably mounted on said guide member, a lever having one of its ends pivotally connected to said sliding block member and having its other end pivotally connected to said door jamb at a position offset from the axis of rotation of said door on its hinges, means for locking said sliding block member against said guide member at any position of travel of said sliding block member on said guide member, said means comprising a ratchet bar mounted for reciprocation on said guide member, said ratchet bar having a pin projecting laterally from each end thereof, said guide member having pockets formed therein to slidably receive said pins, said ratchet bar having ratchet teeth projecting therefrom in a direction opposite said pins, said sliding block member having formed thereon ratchet teeth adapted to mesh with said ratchet teeth formed on said guide member, resilient means interposed between said ratchet bar and said guide member, said resilient means constantly tending to urge said ratchet bar teeth into contact with said teeth formed on said sliding block member, and means for moving said ratchet bar in opposition to said resilient means to effect disengagement of said ratchet teeth of said ratchet bar from said ratchet

teeth formed on said sliding block member, said means comprising an elongated shaft extending longitudinally of said guide member and rotatably supported thereon, one end of said shaft terminating in a crank arm, said shaft carrying a pair of levers fixedly secured thereto for rotation therewith and positioned on said shaft at opposite ends of said guide member, and said levers being adapted to rotate into contact with the remotely-disposed ends of said ratchet bar upon rotation of said shaft to move said ratchet bar out of contact with said sliding block member.

3. A door stop as defined in claim 2, including a mechanism connecting said crank arm with a handle-operated door latch to effect engagement and disengagement of said ratchet bar with said ratchet teeth formed on said sliding block member.

4. A door stop as defined in claim 3, wherein said mechanism includes a vertically-extending member having its lower end pivotally connected to said crank arm and its upper end pivotally connected to one arm of a bell crank lever incorporated in said mechanism and including a horizontally-slidable strip member connecting the other arm of said bell crank lever to the handle of said door latch.

5. A door stop as defined in claim 4, including a mechanism connecting said crank arm with a rotatable handle-operated door latch adapted to transmit motion to said crank arm, said mechanism including a vertically-extending pulling member having its lower end pivotally connected to said crank arm and its upper end connected to said one arm of said bell crank lever incorporated in said mechanism, and including a horizontally-slidable strip member connecting the other arm of said bell crank lever and said door latch, whereby operation of said pulling member in a vertical direction will effect the engagement or disengagement of said ratchet bar teeth with said ratchet teeth formed on said sliding member.

6. A door stop as defined in claim 5, and means for locking said ratchet bar out of contact with the ratchet teeth formed on said sliding member.

7. A door stop comprising an elongated substantially channel-shaped member having a main body portion including a bight from the ends of which project a pair of end walls, said main body portion being mounted on said door with an end wall facing the door jamb from which the door is suspended, a U-shaped guide member having its ends fixedly secured to said end walls and disposed in spaced relation relative to said bight, a bar mounted for reciprocation within said U-shaped guide member, means disposed between said U-shaped member and said bar constantly biasing said bar for movement away from said U-shaped member, lever means pivotally supported on said main body portion and engaging said bar to effect movement of said bar inwardly of said U-shaped member when said lever means are pivoted in one direction, said bar having teeth formed thereon facing outwardly of said U-shaped member, a substantially rectangular sliding block member slidably mounted on said U-shaped member and engaging around said bar, said block member having teeth formed thereon facing said teeth formed on said bar and adapted to mesh therewith, a lever pivotally connected to said block and said jamb, and means connected with said lever and a door handle for said door to effect disengagement of said teeth formed on said bar and block.

8. A door stop as defined in claim 7, wherein said teeth formed on said bar and said block are of the ratchet type.

9. A door stop as defined in claim 7, wherein said teeth formed on said bar and said block are of the rack gear type.

10. In combination with a door-bolt actuating mechanism, a strip member having an end thereof connected with said mechanism and movable therewith as said mechanism moves said door-bolt to its retracted position, said

strip member being supported on said door for reciprocation thereon, a bell crank lever pivotally mounted on said door and having an arm thereof disposed in the path of movement of said strip member, an elongated lever pivotally connected to the other arm of said bell crank lever adjacent the free end thereof, a door stop comprising an elongated substantially channel-shaped main body portion including a bight from the ends of which project a pair of laterally-spaced and substantially parallel end walls, said main body portion being mounted on said door with an end wall facing the door jamb from which said door is suspended, a substantially U-shaped guide member having its opposed ends fixedly secured to said end walls and disposed in laterally-spaced relation relative to said bight, an elongated bar mounted for reciprocation within said U-shaped member, means disposed between said U-shaped guide member and said bar constantly biasing said bar for movement away from said U-shaped guide member, a shaft extending through said end walls and said bight and being rotatably mounted therein, said shaft having one of its ends terminating in a crank arm, means pivotally connecting said crank arm with the other end of said bell-crank lever whereby movement of said bell-crank lever will force said crank arm to rotate and consequently said shaft, a lever for each end of said bar,

15
20
25

said levers having one of their respective ends fixedly secured to said shaft for rotation therewith and their respective other ends constantly engaging the opposed ends of said bar, said shaft, upon movement in one direction, causing said levers to turn and force said bar inwardly within said U-shaped guide member, a sliding block member mounted for reciprocation on said U-shaped guide member, a lever having one of its ends pivotally connected to said sliding block member and its other end connected to said jamb, and interlocking means on said bar and said sliding block engageable to prevent movement of said door when said bar is moved its maximum distance away from said U-shaped guide member.
